R. M. SHAFFER

AUTOMATIC FURNACE REGULATOR

Filed Feb. 20, 1923

Richard M. Shaffer,

Eccleston & Eccleston,

By

Attorney

UNITED STATES PATENT OFFICE.

RICHARD M. SHAFFER, OF BALTIMORE, MARYLAND, ASSIGNOR OF ONE-HALF TO
JOHN W. SMITH, OF BALTIMORE, MARYLAND.

AUTOMATIC FURNACE REGULATOR.

Application filed February 20, 1923. Serial No. 620,243.

To all whom it may concern:

Be it known that I, RICHARD M. SHAFFER, a citizen of the United States, and a resident of Baltimore, in the State of Maryland, have invented certain new and useful Improvements in Automatic Furnace Regulators, of which the following is a full, clear, and exact description.

My invention relates to draft regulators for furnaces, and one of the objects of the invention is to provide a simple, inexpensive and efficient mechanism for automatically regulating the drafts and fuel consumption in steam furnaces, hot water furnaces, hot air furnaces, steam boilers, or any other heating or power plant, either domestic or commercial.

Another object of the invention is to provide an apparatus of this character that may be automatically operated in accordance with air pressure, steam pressure, water pressure, or by the temperature of air, steam or water, or by the temperature of any part of the furnace or boiler or associated parts.

Another object of the invention is to provide a positive automatic control of the ash pit damper, fire door and flue damper, whereby the automatic control is complete instead of partial, and whereby the condition of the furnace is controlled to the same extent and in the same manner as in the manual operation thereof.

A further object of the invention is to provide an apparatus of this character which may be instantly changed from automatic control to manual control, or vice versa.

Still another object of the invention is to provide a time-controlled mechanism by means of which the apparatus may be thrown into automatic operation at any desired time.

Another object of the invention is to provide a device of this nature which is extremely simple in construction and inexpensive in manufacture, and which may be quickly and easily applied to any type of furnace.

Numerous other advantages will be apparent to those skilled in the art to which the invention appertains from the following detailed description when taken in connection with the accompanying drawings, in which:

Figure 1 is a front elevation of the com-

plete apparatus, the mechanism being shown as under automatic control.

Figure 2 is a vertical sectional view of the fire door supporting means.

Figure 3 is a detail sectional view of a supplementary means for supporting and vertically adjusting the fire door.

Figure 4 is a bottom plan view of a releasing mechanism; and

Figure 5 is a detail perspective view of a bracket, showing in outline a bell crank lever mounted thereon.

Figure 6 is a fragmentary plan view of the mechanism associated with the fire door; the link 14 being in section.

Referring to the drawings more in detail, numeral 1 refers to any ordinary type of furnace which is provided with the conventional ash pit damper 2, fire door 3, and flue damper 4.

For purposes of illustration only I have shown mounted on the top of the furnace the ordinary pressure operated diaphragm 5, but it will be understood that in place of this diaphragm I may substitute any other form of pressure or heat-controlled apparatus, as hereinbefore mentioned. A frame 6 is pivotally mounted adjacent to the pressure diaphragm, and this frame carries a bracket 7 in which is mounted an arm 8; the arm being held in adjusted position in the bracket by means of the set-screw 9 or the equivalent. The frame 6 carrying the arm 8 is moved about its pivot in the usual manner by connection with the pressure diaphragm. The arm 8 is also provided with the ordinary adjustable counterbalance weight 10.

A chain 11, or equivalent connecting means, is attached at one end to the flue damper, and its other end is attached to the rear end of the arm 8. Of course, the chain may be attached to the arm in any desired manner, but I prefer to provide the arm with a hook 12 for receiving a link 100 of the chain, as clearly illustrated in the drawings.

Pivotedly attached to the forward end of the arm 8, as by means of a hook 13, is a downwardly extending link 14, which link 105 is pivotally attached at its lower end to the horizontal arm 15 of a bell crank lever mounted on the furnace front adjacent to the fire door. Any preferred means may be employed for pivotally connecting the link 110

and bell crank, but I have shown herein a hook 16 carried by the lower end of the link and adapted to engage an eye in the bell crank lever.

5 A bracket 17 is mounted on the fire door, and this bracket is provided with an eye which is adapted to be engaged by the hook 18; the hook being pivotally connected at its opposite end to the vertical arm 19 of 10 the bell crank lever. The bell crank lever is preferably aligned with the bracket 17 by mounting it on a bracket 34, as clearly shown in Fig. 5.

The link 14 is also provided with a plurality of hook members 20, and a chain 21 is adapted to engage over one of these hooks, while the opposite end of the chain is connected with the ash pit damper 2.

15 The operation of the apparatus thus far described is as follows:

Assume the various parts to be in the position shown in the drawings; then upon a rise in temperature or increase in pressure the thermostatic element or the diaphragm, 20 whichever is employed, will act to cause the arm 8 to move about its pivot, the rear end of the arm being raised and the forward end being lowered. It is obvious that as the rear end of the arm 8 is raised the flue 25 damper will be opened, the amount of opening depending, of course, on the extent of movement of the arm 8; and it will also be apparent that as the front end of the arm 8 is lowered the link 14 will cause the bell 30 crank to rotate about its pivot, and the hook connection between the vertical arm of the bell crank lever and the bracket 17 will cause the fire door to swing to open position, the extent to which the door is 35 opened depending, of course, on the extent of movement of the arm 8. When the forward end of the arm 8 and the link 14 move downwardly, it will also be noted that the chain connection 21 between the link and the 40 ash pit damper permits the latter to move by 45 gravity toward closed position.

The extreme simplicity of the construction, and the effectiveness of the invention, as so far described, will be obvious. As the 50 arm moves in one direction the flue damper is opened, the ash pit damper is closed, and the fire door is opened, thereby checking the fire in exactly the same manner that is employed in the manual control of a furnace; and as the arm is moved in the opposite direction the flue damper is closed, the ash 55 pit damper is opened, and the fire door is closed, thereby creating a favorable draft for increasing the intensity of the fire.

60 It will be understood, of course, that the various parts will be operated automatically at such times as may be necessary in order to maintain a uniform pressure or temperature, and that the movements will be effected 65 through the operation of the thermostat or

diaphragm, as previously described. For purposes of illustration only I have shown employed herein a pressure-operated diaphragm, and the apparatus is set for the desired pressure by the adjustment of the counterbalance weight 10 along the arm 8 in the usual manner; but it is to be noted that the sensitiveness of the device may be varied in my construction by moving the arm 8 bodily and securing it in adjusted 70 position by means of the set-screw 9.

75 It is also to be noted here that the fire door may be instantly released from or connected with the automatic control by merely disconnecting or connecting the hook 18 with the bracket 17. Also the ash pit damper 2 may be rendered inoperative by removing the chain 21 from the upper hook 20 and placing it on the lower hook 20; and the flue damper 4 is rendered inoperative by 80 removing the chain 11 from the hook 12.

85 It is highly desirable, of course, to bank the fires and check the draft during the night, and to provide some means whereby during the early morning hours the position of the damper will be automatically changed to create a favorable draft and thus build up the fire, and I will now describe a most simple arrangement by which this is accomplished.

90 Mounted on the beams, or the like, in the cellar is a plate 22 provided with a suitable slot 23. Pivottally attached to the forward portion of the arm 8 is an upwardly extending rod 24 provided with a notch for 95 engaging an edge of the slot 23. To set the furnace for the night it is only necessary to move the arm 8 and rod 24 downwardly until the notch becomes aligned with the edge 100 of the slot, and then moving the rod over so that the notch will engage the edge, thereby securing the parts in position to check the fire during the night. When so positioned the ash pit damper is closed, the flue 105 damper is open, and the fire door is open. The various elements will remain in this position until the rod 24 is released, whereupon the counterbalance weight 10 will cause the position of the parts to be reversed to create a draft and to build up the fire.

110 For the purpose of releasing the rod 24 I have provided a trigger 25 which is pivotally mounted on the plate 22 adjacent to the rod 24, so that as the trigger is moved against the rod it will trip the same, releasing it 115 from engagement with the plate, and permitting the dampers, etc., to return to automatic control in accordance with furnace 120 conditions. It will be observed that the trigger is so arranged that it may be reversed to suit different installations; the 125 reversed position being indicated in broken lines.

130 The trigger 25 may be moved by any pre-

ferred form of timing mechanism, but I have illustrated herein a conventional alarm clock 26 provided with any ordinary arm 27 for winding the same. A chain 28 is attached to the winding arm 27 and extends upwardly over a pulley 29 and thence over to the trigger 25 to which it is attached. An abutment 30 is provided to limit the unwind-ing movement of the arm 27.

10 The operation of this simple construction will be obvious from the foregoing description. The alarm is set for a certain hour and the winding arm 27 is rotated through approximately a half a turn, so that it would be in a position opposite to that shown in the drawings. At the hour set the alarm mechanism will be released and the arm 27 will begin to move downwardly, thereby exerting a pull on the chain 28 and drawing 20 the trigger over to trip the rod 24. The purpose of the abutment 30 is merely to limit the extent of movement of the winding arm, thereby avoiding the necessity of fully winding the alarm each time the apparatus is set.

It should be mentioned here that at times it may not be desired to check the fire to the full extent during the night, and in such cases it is only necessary to remove the hook 30 18 from engagement with the fire door, thereby permitting the latter to be closed for the night.

In the ordinary construction of furnaces the doors are loosely mounted on the hinges, 25 so that they may be raised to free the latch and then be swung to open position; and it will be understood that in the present invention the movement of the fire door is automatically controlled, and hence some means 40 must be provided for freeing the latch in order that the fire door may be opened. For this purpose I have provided a set-screw 31 which is adapted to engage the lower pintle 32 of the fire door, thereby moving the door 45 upwardly the desired extent to free the latch. In some installations the fire door may be so loosely mounted that the set-screw is not adequate for the purpose, and in such instances I employ a plate 33 which is aper-tured to receive the upper pintle. In the use 50 of this plate it is moved to the right (Fig. 3) until the door has been lifted slightly, and the end of the plate is then turned at an angle, as indicated in Fig. 3, thereby 55 securing the door in its adjusted position; the set-screw 31 then being operated to lift the door the remaining distance required to free the latch.

Whenever the fire door is released from 60 automatic or time control, and it is to be locked in closed position, it is apparent that it is only necessary to rotate the set-screw, thereby lowering the door and engaging the latch.

65 From the foregoing description it will be

apparent that I have devised an apparatus which is most simple in construction and inexpensive in manufacture, and one which may be quickly and easily applied to a furnace; that, in accordance with my invention, the flue damper, ash pit damper and fire door will be automatically controlled in accordance with the desired conditions in the furnace or boiler, and that this automatic control of the drafts is accomplished 70 in exactly the same manner as is employed in the manual operation of a furnace; that the apparatus may be instantly changed from automatic control to manual control; and that, in accordance with the timing feature of the invention, the fire may be checked for the night, and at any hour desired the apparatus will be thrown into automatic operation, whereupon the dampers, etc., will move to a position to create a favorable draft for building up the fire.

In accordance with the patent statutes, I have described what I now believe to be the best embodiment of the invention, but I do not wish to be understood thereby as limiting myself or the scope of the invention, as many changes and modifications may be made without departing from the spirit of the invention; all such I aim to include in the scope of the appended claims.

What I claim as new and desire to secure by Letters Patent is:

1. In a furnace, a pivoted arm, an automatic control for moving said arm, flexible connections between the arm and the flue damper and ash pit damper, whereby the flue damper and ash pit damper are positively opened and gravity closed, and a positive link connection between said arm and the fire door for opening and closing said door.

2. In a furnace, a fire door, a bell-crank lever adjacent to the fire door, a link pivotally attached to one arm of the bell-crank lever, said link adapted to engage the fire door, a second link pivotally attached to the other arm of the bell-crank lever, a flexible member having one end removably attached to the second mentioned link and having its other end connected with the ash-pit damper, 115 a pivoted arm connected to the second-mentioned link, and an automatic control for moving the arm.

3. In a furnace, a fire door, a bell-crank lever adjacent to the fire door, a link pivotally attached to one arm of the bell-crank lever, said link adapted to engage the fire door, a second link pivotally attached to the other arm of the bell-crank lever, a flexible member having one end attached to the sec- 120 ond-mentioned link and having its other end connected with the ash-pit damper, a pivoted arm connected to the second-mentioned link, an automatic control for moving the arm, a rod extending upwardly from 130

said arm, a trigger for engaging the rod in one position thereof, and time controlled means for releasing the trigger.

4. In a furnace, a fire door, a bell-crank lever adjacent to the fire door, a lug mounted on the fire door and extending outwardly beyond the plane of the door hinges, a link pivotally attached to one arm of the bell-crank lever, the other end of said link adapted to detachably engage said lug, a second link pivotally attached to the other arm of the bell-crank lever, a flexible member having one end attached to the second-mentioned link and having its other end connected with the ash-pit damper, a pivoted arm connected to the second-mentioned link, and an automatic control for moving the link.

5. In a furnace, a pivotally mounted arm, an automatic control for said arm, a flexible connection between the rear end of said arm and the flue damper, a link pivotally attached to the forward portion of the arm, a positive connection between said link and the fire door for opening and closing the door, and a flexible connection between said link and the ash pit damper.

6. In a furnace, a horizontally swinging fire door, said door being loosely mounted, a set-screw adapted to engage the lower pintle of the door whereby the door may be raised to free its latch, a bell crank lever adjacent the door, connecting means between the door and one arm of the bell crank lever, a link connected to the other arm of the bell crank lever, and means for moving said link in accordance with furnace conditions.

7. In a furnace, a horizontally swinging fire door, said door being loosely mounted, a plate associated with the upper pintle of the door for taking up a portion of the loose connection, a set-screw adapted to engage the lower pintle of the door whereby the

door may be raised to free the latch, a bell crank lever adjacent the door, connecting means between the door and one arm of the bell crank lever, a link connected to the other arm of the bell crank lever, and means for moving said arm in accordance with boiler conditions.

8. In a furnace, a pivoted arm, an automatic control for moving the arm, connections between the arm and the flue damper, ash pit damper and fire door, a rod pivotally attached to the arm, a slotted plate, said rod received in the slot of the plate, said rod provided with a notch adapted to engage an edge of the slot to hold the arm in non-automatic control position, and a trigger for releasing the rod to permit the arm to return to automatic control position.

9. In a furnace, a pivoted arm, an automatic control for said arm, connections between said arm and the furnace dampers, a rod carried by the arm, a plate adjacent said rod, the rod being provided with a notch adapted to engage the plate to hold the arm in non-automatic control position, a trigger pivotally mounted adjacent to the rod, a timing mechanism, a flexible connection between the timing mechanism and the trigger, whereby the latter may be moved to release the rod to permit the arm to return to automatic control position.

10. In a furnace, a horizontally swinging fire door, said door being loosely mounted, a plate associated with the upper pintle of the door for taking up the loose connection whereby the door is raised to free it from its latch, a bell-crank lever adjacent the door, connecting means between the door and one arm of the bell-crank lever, a link connected to the other arm of the bell-crank lever, and means for moving said arm in accordance with boiler conditions.

RICHARD M. SHAFFER.
